UNITED STATES PATENT OFFICE.

ROBERT W. LYLE, OF NEW YORK, N. Y.

DRIER FOR CLAY PRODUCTS.

No. 834,584.

Specification of Letters Patent.

Patented Oct. 30, 1906.

Original application filed November 10, 1904, Serial No. 232,072. Divided and this application filed February 25, 1905.
Serial No. 247,384.

To all whom it may concern:

Be it known that I, ROBERT W. LYLE, a citizen of the United States, and a resident of New York, in the county and State of New York, have invented certain new and useful 5 Improvements in Driers for Clay Products, of which the following is a specification.

This invention relates to driers for clay products; and it has particular relation to an 10 improved drier which is especially designed for use in systems or plants for drying and burning vitrified clay products, such as underground-conduit sections for electric wires, and analogous products.

15 In drying and burning plants of the character just stated the drier is usually arranged intermediately with relation to the factory and the kiln or burning media, the drier being provided with a series of tunnels or compartments in which the "green" conduit-sections or other clay products are stored on hand-cars during the drying period.

20 The improved drier constituting my present invention has direct relation in its subject-matter and adaptability to the general system and means for drying and burning clay products which is described and illustrated in my previous application for patent, Serial No. 232,072, filed November 10, 1904, 25 from which application the subject-matter of this present application is divided.

25 Driers or dry-houses designed for and adaptable to the special purposes above stated have usually heretofore been heated by conveying and introducing into the interior area of the tunnels or drying-compartments a limited percentage of the products of combustion from the kilns, under which circumstances the noxious gases and fumes in the 30 products of combustion occupy the interior area of the drying-compartments, which condition is objectionable, disadvantageous, and expensive in the drying of clay products such as those above set forth. The drier has also 35 heretofore been provided with independent heating media—for instance, furnaces at the ends of the drying tunnels or compartments and feeding-flues in the latter, which is expensive both in the consumption of fuel and labor 40 required. The disadvantages and lack of economy in the previous systems of heating the drier are fully set forth in my above-mentioned copending application for patent and do not require further specific mention here.

The object of my present invention is to 55 provide an improved drier which is adaptable to the purposes and relationship above set forth and which is also adaptable for effective use in the general drying of clay products.

A further object of my invention and improvements is to provide a drier of the class herein set forth which will be simple, inexpensive, and effective in construction and in which the maximum of efficiency, convenience, cleanliness, and rapidity and economy of operation will be secured.

This present application is divided from my original application for patent for systems and means for drying and burning clay products, filed November 10, 1904, Serial 70 No. 232,072.

In the drawings, Figure 1 is a diagrammatic plan view showing my improved drier (the roof being removed) in its relationship or association with the factory and kiln elements of 75 a general system or plant for drying and burning clay products. Fig. 2 is a detail horizontal sectional view illustrating one of the drying tunnels or compartments of the drier and taken on a plane above the heat-radiating 80 elements, half of said view having the trackage removed and parts being broken away to show features of construction. Fig. 3 is a detail vertical sectional view taken through the drier on the plane of one of the drying 85 tunnels or compartments and through one of the longitudinal heat-radiating flues therein. Fig. 4 is a detail vertical sectional view taken through the drier on a plane transversely of one of the drying tunnels or compartments. 90 Fig. 5 is a sectional view corresponding to Fig. 4 and illustrating a modification in the construction of the longitudinal heat-radiating flues in the drying tunnel or compartment. Fig. 5^a is a detail vertical sectional view illustrating the relationship of the modified longitudinal heat-radiating flues shown in Fig. 5 to the transverse heat-radiating flues of the 95 drier. Fig. 6 is a top or plan view of part of the roof of the drier, illustrating the ventilating elements therein. Fig. 7 is a detail vertical sectional view illustrating the construction of the expansion and contraction and fume-proof joint at the end of the top plate of the main transverse heat-radiating flues of 100 the drier. Fig. 7^a is a sectional view corresponding to Fig. 7 and illustrating a modified construction of said end joint. Fig. 8 is a de-

tail plan view; partly broken away, showing the connection of the products-of-combustion flues from the fans with the main transverse heat-radiating flue of the drier.

5 Corresponding parts in all the figures are denoted by the same reference characters.

Referring to the drawings, K designates a series of kilns, from which extend suitable products-of-combustion flues, as indicated at

10 1, 2, 3, 4, and 5, which are designed to connect with the heating system of the drier.

F designates fans, which are arranged to draw the products of combustion from the kilns and force the same to operative service

15 in the heating system of the drier, these fans being preferably arranged in connection with the terminal flues (indicated at 4 and 5) of the kiln system. The foregoing elements are comprised in the kiln system, the products of

20 combustion from which are especially intended to be utilized in my improved drier. The factory system is indicated at F^c in Fig. 1 and is shown as arranged at the initial or opposite side of the drier from the kiln system,

25 the drier being intermediate with relation to the kiln system and the factory.

D designates the drier or drying-house, which is preferably arranged transversely with respect to the kiln system and factory

30 and may be in close relationship thereto, as indicated in Fig. 1. The drier comprises a building having end walls d and d', respectively, preferably extending transversely of the kilns and factory system, and side walls

35 d² d³, extending from front to rear, a suitable roof d³ being provided. The drier may be its main arrangement and compartment in structure of any suitable or adapted construction and preferably has a central com-

40 partment d⁴ extending from front to rear and forming a storage-room or trackage-space, suitable trackage for the hand-cars carrying the product being provided in this compartment, as at st, which trackage is in operative

45 association with a storage-trackage, as at st², provided in the kiln-yard and communicating with the general kiln-yard trackage yt, extending between the kilns. At each side the central compartment d⁴ is provided a se-

50 ries of drying tunnels or chambers, as at d⁵, in parallel relationship and extending from front to rear, said drying-tunnels being divided by partitions or walls, as at d⁶. Any desired capacity in the number of drying-

55 tunnels may be employed, and each tunnel is provided with a series of parallel longitudinally-extending tracks, as at tt, for the hand-cars carrying the product to be dried. Any desired number of tunnel-tracks tt may be

60 employed, and the whole set of the same can communicate with the central-compartment trackage st and with the yard-trackage st² by means of a transfer-track, as at tt², extending transversely with respect to the compart-

65 ments or chambers of the drier and provided

longitudinally of both the end walls d and d', as shown.

Within the drier D, extending transversely of the whole series of drying tunnels or chambers and at each end thereof, are flues 6 and 7, respectively, built below the ground or floor-plane. These flues 6 and 7 may be constructed of brick or masonry or other suitable material. Suitable doors or closed openings, as at d⁷, may be provided for the compartments or chambers of the drier in the walls d and d' of the latter. The fan-flues 5 are shown extending to one of the main transverse drier-flues 6, preferably entering the latter at a common central point, as shown, 80 and at this point the drier-flue 6 is preferably provided with a double deflector, as shown at d⁸, so that the heating products from the fans will be diverted in opposite directions to feed the series of drying-tunnels at each side the 85 central compartment of the drier.

The main underground yard-flues 1 to 5, inclusive, are designed to retain the heat and are consequently of such uniform structure that they will not radiate the same, the whole 90

heat value of the kilns being designed for use in the drier; but the drier-flues 6 and 7 are designed to radiate the heat, and for this purpose they are provided with radiating tops d⁹. These radiating tops are preferably 95 formed of bowed or arched longitudinal metallic plates d⁹, resting upon continuous shoulders or offsets d¹⁰ on the masonry side walls d¹¹ of the flues 6 and 7, and their ends can rest upon curved shoulders or offsets d¹² 100 upon the end walls d¹³ of said flues, as shown in the modification illustrated in Fig. 7^a. To form a tight joint against the escape of the heating products or noxious gases or fumes into the interior of the drying-chamber and 105

form a tight joint against the escape of the heating products or noxious gases or fumes into the interior of the drying-chamber and 110

provide for the contraction and expansion of the metallic plate d⁹, I fill in, above the edges of the arched plate where they rest upon the supporting-shoulders, with sand, as shown at d¹⁴, which forms an effect- 115

ive joint for both purposes mentioned. Any other suitable joint means may, however, be employed. In constituting the joint at the 120

ends of the arched plates d⁹ the terminal ends of the plates, as at d¹⁵, can be received by 125

corresponding recesses d¹⁶ in the end walls d¹³ of the flues 6 and 7, which permits of contraction and expansion of the plates in said 130

end recesses and, furthermore, does not permit of escape of gases or fumes, this construction being shown in Fig. 7. In connection with the joint means described it will be understood that the force of the draft in the drier-flues is continuous to the main stacks, (shown at S,) which will be hereinafter de- 135

scribed, and overcomes any tendency to emission of gases or fumes at the joint-points. In the drying tunnels or chambers d⁵ are provided flues 8, extending from front to rear longitudinally of the tunnel and com- 140

municating at their ends with the main drier intake-flue 6 and outlet-flue 7, respectively. The flues 8 are radiating-flues and may be of tubular cylindrical form and constructed of metal. They are arranged below the ground or floor-plane, one or more tubes extending longitudinally under the tunnel-track upon which stand the cars carrying the product to be dried, and when more than one track is provided in the tunnel the flues 8 are correspondingly arranged under each track. With a plurality of tracks and their under flues 8 the flues may be divided or separated by masonry walls or partitions, as at t^3 , which divide the space under each tunnel-track into separate flue-compartments t^4 , and said partitions can also serve as a rest or support for the ties or sleepers t' , upon which the tunnel-tracks $t t'$ are laid. The flues 8 may be supported intermediately of their ends by masonry cross-walls, as at t^5 , extending between the partition-walls t^3 , or in any other suitable manner.

To provide a tight joint against escape of gases or fumes and to furthermore effectively meet contraction and expansion of the metallic tunnel-flues 8 at their point of connection at each end with the main drier-flues 6 and 7, I prefer to employ a construction in which a supplementary wall t^6 , of masonry or other suitable material, is arranged a short distance beyond the inner side walls d^{11} of the flues 6 and 7, and the end portions t^7 of the flues 8 pass through corresponding openings t^8 in both of the walls t^6 and d^{11} . A gasket or ring of asbestos or other suitable material may surround the flues 8 in the openings t^8 , as shown at t^9 , and the space between the walls t^6 and d^{11} may be filled in with a packing t^{10} , of sand or other suitable material. The joint thus produced is not affected by contraction or expansion of the flues 8, and the sand packing avoids escape of gases or fumes.

The tunnel-flues 8 are provided, preferably at each end, with suitable dampers t^{11} , whereby the flues may be shut off from heat connection and the tunnels independently governed, as desired. When a plurality of flues 8 are provided in each tunnel, the set of dampers t^{11} may be connected and simultaneously operated by any suitable operating mechanism, such as a connecting-rod t^{12} . Manholes t^{13} may also be provided at suitable intervals in the flues 8 to enable cleansing and inspection, as desired.

A circulation of the hot air in the drier and tunnels or chambers may be effected in any suitable manner. I prefer to employ the construction herein illustrated, which comprises a series of vertical air vents or passages v , extending downwardly in the partition-walls d^6 , which divide the drying tunnels or chambers, these walls being constructed of brick or masonry. At their lower ends the

passages v have an outlet connection v' opening into the space or flue-compartment t^4 , surrounding the flue 8 and on a plane below said flue. At their top ends the passages v open through the roof of the drier D and may be continued, as at v^2 , through extensions v^3 , projecting above the roof, the inlet end v^4 of the passage being protected against the weather by a suitable cap v^5 . These passages may be governed by dampers of any suitable construction, (not shown,) which may be arranged at their top ends, if desired. The hot air ascending in the tunnels will create a strong draft for drawing in the cold air through the passages v and delivering it adjacent to the flues 8. In the roof of the drier, over the tunnels, are provided hot-air-outlet chimneys, as at v^6 , to enhance the draft and circulation, which outlets may be protected by a suitable cap v^7 and may be governed by dampers of any suitable construction, (not shown,) if desired.

When a plurality of flues 8 and flue spaces or compartments t^4 are employed in each drying-tunnel, the outlet connection v' of the air-passages v may be continued transversely of the tunnel, in the intermediate cross-walls t^5 , under the flues 8, and through the dividing-partitions t^3 , under which circumstances the outlet-openings v^8 for the air-passages v will extend from the outlet connection v' upwardly in the cross-walls t^5 , as shown.

To enable very quick cooling of the drier D or its respective tunnels or compartments, a series of skylights v^9 are provided in the roof of the drier over each compartment and have a top v^{10} , which may be opened or closed and governed by suitable regulating mechanism, as at v^{11} . The general construction of the drier thus involves provision for thoroughly opening up and cooling it, as desired. The provision of suitable damper arrangements at suitable points in any of the main kiln-yard flues before they reach the inlet drier-flue 6 will enable the quick and entire shutting off of heat to the drier, as desired.

The main outlet drier-flue 7 which corresponds in construction and arrangement to the inlet-flue 6, has at each end an outlet extension 9, which extensions respectively open into main stacks S. These stacks S in the general heating arrangement for the drier, as herein illustrated and described, by means of all the products of combustion from the kiln system specifically serve as the outlet-stacks for the whole kiln system by reason of the intermediate flues 1 to 9 extending between the kilns and stacks, as hereinbefore described. In lieu of two stacks S one may be employed. The stacks S are located intermediately between the drier D and the factory F^o, and the drier D is intermediately between the main stacks S and the kilns which the stacks serve. The outlet extension-flues 9 are underground and are preferably provided with

dampers s^d , which may be closed to shut off the heat circulation in the flue system of the drier. Said circulation is also effectively governed by the starting or stoppage and speed of the fans F.

In lieu of the flue construction and arrangement in the drying tunnels or chambers as hereinbefore described I may employ in the tunnels a flue arrangement practically the same in construction as the main drier inlet and outlet flues 6 and 7, as shown in the modification illustrated in Figs. 5 and 5^a of the drawings. In this modified construction a flue 8^m is provided under each tunnel-track and is the same in construction as the flues 6 and 7 with the metallic top plate d^o and the same construction and arrangement for providing for contraction and expansion of the plate and the sand packing at the joints for providing against the escape of gases and fumes. The flues 8^m communicate at their ends with the main flues 6 and 7 through openings m in the side walls d^{11} of the latter, and the side walls of the flues 8^m are formed by the walls or partitions t^3 , which support the tunnel-tracks, and by the tunnel walls or partitions d^6 . When this modified arrangement is employed, the outlet connection v' of the air-passages v will open on a plane above the metallic top plates d^o of the flues 8^m, (see Fig. 5,) and the dampers for the tunnel-flues, as at m' , can be provided at the openings m .

In the drying-tunnels the usual point of least heat, and consequently the point where heat is most needed, is at the ends of the tunnel, and it is to effectively meet this requirement and overcome the objection just noted that I provide the main transverse drier-flues 6 and 7 at the ends of the tunnels.

When the dampers t^{11} of the tunnel-flues 8 are independently mounted in their operative relation to the respective flues 8, the latter can be cleaned of any deposit of the products of combustion therein automatically and without the use by workmen of the manholes t^{13} by employing the high-power draft of the fans F through one or more of the flues 8, the flues to be cleaned being individualized by shutting off the dampers of the other flues 8.

While I have herein illustrated and described my improved drier in its special relationship to a system of heating by means of all the products of combustion conveyed from a kiln or kilns while in course of burning, it will be understood that the general construction and arrangement of parts and features as comprised in my improved drier are adaptable to service in relation to any other suitable heating media.

I have shown at o' openings in the metallic top plates of the drier-flues 6, 7, and 8 or in the tops of the tubular longitudinal metallic flues of the drying tunnels or compartments,

these openings being normally closed by caps or covers, as shown at o^2 . These openings and their closures may be employed under special conditions—for instance, when the products of combustion being fed to the flues 70 are not noxious or otherwise objectionable, which would sometimes be the case when the kilns are not operating in the process of salt glazing. Under these circumstances the heating media could be passed into the interior of the drier through these openings. 75

It will be understood that when the tubular metallic flues are employed in the drying-tunnels I may in lieu of using only one large flue under each tunnel-track, as shown in Fig. 80 4, employ a set or plurality of said tubular metallic flues under each track.

The operation and advantages of my invention will be readily understood by those skilled in the art to which it appertains. My 85 improved drier, in connection with the general kiln system and heating media to which it is especially adapted, provides a general means under which all the manufacturing elements are compactly and closely associated—to wit, 90 the factory, drier, and kilns in successive operative arrangement and for correlative operation in which all heat values are utilized—it enables the use of absolutely all the products of combustion from the kilns at all times 95 of kiln operation for service in the drier; it employs but one heating expenditure for the use of both the drier and kilns and for both the operations of drying and burning; it makes the drier an intermediate part of the 100 kiln system; it obviates the disadvantage of having any products of combustion free within the interior area of the drier and enables safe and convenient operation within the drying-tunnels at all times desired; it 105 provides for the convenient regulation of degrees and circumstances of operation in both the drying and burning elements at all times, and it secures maximum utility and economy in construction and in operation. 110

I do not herein claim specifically the general features of the kiln system and other parts of the manufacturing elements which are associated with and related to my improved drier embodied in my present application, said kiln system and other related manufacturing elements being included in my original application, filed November 10, 1904, Serial No. 232,072, from which original application the present application for the 120 drier has been divided.

I do not desire to be understood as limiting myself to the detail features of construction and arrangement as herein shown and described, as it is evident that variations and 125 modifications may be made in the features of construction and arrangement, in the adaptation of the invention, and improvements to various conditions of use without departing from the spirit and scope of my invention. 130

therefore reserve the right to all such variations and modifications as properly fall within the scope of my invention and the terms of the following claims.

5 I claim and desire to secure by Letters Patent—

1. As an improvement in means for drying clay products, a drier having a main large flue-chamber, as at 6, extending across the 10 end of the drying tunnel or compartment and contained entirely within the drier, a radiating top for said flue 6 extending across the drying-tunnel and exposed directly therein, relatively smaller heat-radiating flues 15 extending from said large end flue 6 longitudinally in the drying tunnel or compartment, a kiln system exterior of the drier, and means for conveying the products of combustion of the kiln system to said flue 6, for 20 the purpose set forth.

2. As an improvement in means for drying clay products, a drier having a main large flue-chamber, as at 6, extending across the end of the drying tunnel or compartment 25 and contained entirely within the drier, a radiating top for said flue 6 extending across the drying-tunnel and exposed directly therein, heat-radiating flues extending from said large end flue 6 longitudinally in the drying 30 tunnel or compartment, means for independently closing said longitudinal flues from the end flue 6, a kiln system exterior of the drier, and means for conveying the products of combustion of the kiln system to said flue 6, for the purpose set forth.

3. As an improvement in means for drying clay products, a drier having a high-heat externally-closed conducting-flue, a main flue into which said conducting-flue opens, a 40 double support at the point of communication of the conducting-flue with the main flue, which supports movably receive and surround the conducting-flue, and a filling or packing surrounding the conducting-flue between the members of the double support.

4. As an improvement in means for drying clay products, a drier having a heat-conducting flue, a metallic heat-conducting flue entering the wall of said first flue, a supplementary wall outside the wall of said first flue 50 and receiving the metallic flue and a filling or packing surrounding the metallic flue between said walls, whereby a loose-joint connection is formed.

5. As an improvement in means for drying clay products, a drier, externally-closed heat-radiating flues contained within the drier, a products-of-combustion flue communicating

with the said first flues, forced-draft means communicating with the products-of-combustion flue, and means for closing one or more of said first flues from the products-of-combustion flue so that the forced draft can be directed solely through one or more of the flues, for the purpose set forth.

6. As an improvement in means for drying clay products, a drier having heat-radiating flues provided with a longitudinal shoulder or support at the inner side of the flue-walls, an arched metallic top springing between 70 said walls and having its longitudinal edges resting upon said supports, and a granular packing covering said longitudinal edges.

7. As an improvement in means for drying clay products, a drier having externally-closed heat-radiating flues extending in the drying tunnel or compartment and comprising a radiating top, a kiln system exterior of the drier, means for passing the products of combustion from the kiln system to said 80 flues, openings o^1 in said flues arranged in the line of passage of said products of combustion, and a closure o^2 for said openings, for the purpose set forth.

8. As an improvement in means for drying 85 clay products, a drier having a plurality of drying tunnels or compartments, heat-radiating flues contained in the respective compartments and connected in system, a source of heat-supply exterior of the drier, means 90 for passing said heat-supply from said source to said flues, forced-draft means communicating with said passage means, and means for independently closing said flues against the system connection and against the forced- 95 draft means so that the forced draft can be directed solely through an individualized set of said flues, for the purpose set forth.

9. As an improvement in means for drying 100 clay products, a drier having a high-heat-conducting flue, a main flue into which said conducting-flue opens, a double support at the point of communication of the conducting-flue with the main flue, which support movably receives and surrounds the conducting- 105 flue, and a filling or packing surrounding the conducting-flue between the members of the double support.

In testimony whereof I have signed my name in the presence of the subscribing witnesses.

ROBERT W. LYLE.
